UNITED STATES PATENT OFFICE.

EDWIN A. McKOY, OF NEW ORLEANS, LOUISIANA.

SAP-RECEIVING RECEPTACLE AND SUPPORT THEREFOR.

No. 825,237.

Specification of Letters Patent.

Patented July 3, 1906.

Application filed February 1, 1906. Serial No. 299,021.

To all whom it may concern:

Be it known that I, EDWIN A. McKOY, a citizen of the United States, residing at New Orleans, in the parish of Orleans and State 5 of Louisiana, have invented certain new and useful Improvements in Sap-Receiving Receptacles and Supports Therefor; and I do hereby declare the following to be a full, clear, and exact description of the invention, 10 such as will enable others skilled in the art to which it appertains to make and use the same.

This invention relates to improvements in receptacles for receiving sap from trees, and 15 particularly to the apron therefor.

The object of the invention is the improvement of the construction of the apron which supports the receptacle upon a tree.

With this and other objects in view the invention 20 consists of certain novel constructions, combinations, and arrangements of parts, as will be hereinafter fully described, illustrated in the accompanying drawings, and more particularly pointed out in the 25 claims hereto appended.

In the drawings, Figure 1 is a perspective view of my improved apron in position on a tree, showing the receptacle supported upon said apron. Fig. 2 is a transverse sectional 30 view of my apron, showing the manner in which it is secured to a tree. Fig. 3 is a perspective view of my apron, which is provided with a straight upper or rear longitudinal edge. Fig. 4 is a perspective view of an embodiment 35 of my improved apron, which is provided with an inwardly-curved upper longitudinal edge.

My improved apron is preferably formed from a single piece of sheet metal and comprises 40 a flat body 1, which is provided with an upper or rear straight edge 2 and a lower or front flanged edge 3. The flanged edge 3 is angular or curved transversely, forming a hook. I preferably terminate the angular or 45 transversely-curved flange short of the ends of the body 1, as at 3' 3'. The ends of the body 1 are provided with converging flanges 4. These flanges are formed by bending up a portion of the body at right angles 50 thereto. It is noted that said flanges 4 4 converge toward the front flanged edge 3.

In Fig. 4 the apron is similarly constructed

to the apron depicted in Fig. 3, with the exception that the upper or rear longitudinal edge 5 is curved inwardly throughout its 55 length.

Either one of my improved aprons is fastened to a tree by inserting the apron into an incision 6, Fig. 2, formed by a saw or any suitable instrument, deep enough to allow the 60 apron to be shoved in and to slide upward into the tree. The gum oozing out cements the apron into the tree, so that it will not be dislodged. A niche or cut 7 is made in the tree contiguous to the incision 6; but said 65 niche is not as deep as the incision. The receptacle 8 is suspended, by means of a flange 9, upon the transversely-curved or angular flange of the apron. It is to be noted that the receptacle is provided with a trans- 70 versely-curved flange which extends inwardly and permits the receptacle to be positioned upon the apron by sliding it longitudinally upon said apron from one end. The receptacle 8 is removed from the apron by 75 sliding it longitudinally the entire length of the apron and off of the same at one of its ends.

By the word "unobstructed" in this specification in reference to the upper penetrating edge of the apron I wish it to be understood 80 that I mean an edge which is not provided with any flange, prong, or extension and an edge that is capable of being quickly inserted into an incision in a tree, the edge being unbroken and without any obstruction to the 85 position of the tree.

What I claim is—

1. An apron, constituting a support for a sap-receiving receptacle, comprising a body provided with a transversely-curved flange 90 formed upon its lower, longitudinal edge, flanges formed upon the ends of said body and converging toward the lower longitudinal edge, the upper, longitudinal edge of said apron being unobstructed for facilitating the 95 positioning of said apron upon a support.

2. A sheet-metal apron, constituting a support for a sap-receiving receptacle, comprising a body provided with a transversely-curved flange formed upon its lower, longitudinal edge, said flange terminating short of 100 the ends of said body.

3. An apron of the class described, comprising a body provided with converging

flanges upon its ends, and with a transversely-curved flange formed upon its lower, longitudinal edge, said angular flange terminating short of the converging flanges formed upon said body.

4. A sheet-metal apron of the class described, comprising a body provided with a longitudinally-extending, inwardly-curved, upper edge and with a receptacle-supporting

flange formed upon the lower, longitudinal edge.

In testimony whereof I affix my signature in presence of two witnesses.

EDWIN A. McKOY.
